H. M. BOE

OIL DISPLAY DEVICE

Filed Dec. 29, 1927

FIG. 1

FIG. 3

FIG. 2

Inventor
HANS M. BOE

By *Paul A. Bloom*
Attorneys

UNITED STATES PATENT OFFICE.

HANS M. BOE, OF MINNEAPOLIS, MINNESOTA, ASSIGNOR TO BOE MANUFACTURING COMPANY, OF MINNEAPOLIS, MINNESOTA, A CORPORATION OF MINNESOTA.

OIL-DISPLAY DEVICE.

Original application filed March 16, 1927, Serial No. 175,903. Divided and this application filed December 29, 1927. Serial No. 243,349.

This invention relates to improvements in a device for displaying liquid, ordinarily for advertising purposes, and is divisional of my application for oil display devices, filed 5 March 16th, 1927, Serial Number 175,903.

An important object of the invention is to provide means whereby large bubbles may be successively produced in a liquid. Another important object is to provide means for producing the bubbles at timed intervals. A more specific object is to provide an arrangement whereby only single large bubbles are formed and delivered alternately from opposite sides of the bubble-forming device, which 10 device is automatically operated as the result of bubble formation to release the bubble, the results being produced by displacement.

Features of the invention include the broad idea of producing bubbles in the manner set 20 forth, along with the manner of automatically operating the device as the result of displacement, along with all the details of construction.

Advantages of the device will appear from 25 the description of the drawings forming a part of this application, and in said drawings

Figure 1 is a vertical section through a receptacle showing my device applied for forming bubbles within the liquid contained 30 in the receptacle;

Figure 2 is an enlarged detailed sectional view corresponding to Figure 1; and

Figure 3 is a fragmentary plan illustrating the bubble-forming device.

Numeral 1 represents a suitable base 35 grooved as at 2 and having packing 3 therein. The numeral 4 represents a tube of transparent material such as glass having its lower end seated upon the packing. The tube is supported and clamped to form a water tight connection with the packing by means of a plate 5 and bolts 6 arranged substantially as shown. There may be a number of receptacles 4 mounted side by side, as suggested in a 40 fragmentary manner at the right of Figure 1. Means for delivering fluid beneath the element in this instance comprises a pipe having an upstanding portion 7 projecting upwardly through the plate 1 and secured by

means of the packing gland construction 8. 50

The bubble-forming element 9 is formed substantially as shown and is pivotally mounted as at 10 upon upstanding arms 11. The element is of hollow configuration and has a central partition or division element 12. 55 The end walls 13 are cut away as at 14, and the height of the division element is such that its lower end 16 can swing to occupy the positions respectively shown in full and dotted lines in Figure 2. The lower edges 17 form 60 stops to limit the oscillatory movement.

The arrangement is such that air is first delivered into one pocket which gradually displaces the liquid in a manner shown at 18 in Figure 1, finally resulting in raising or 65 rocking the element, to release the bubble in the manner shown in Figure 1. This release places the opposite pocket in a position to receive the delivered air, and the cycle of filling and releasing is repeated. Bubbles are thus 70 alternately released from opposite sides of the element.

I claim as my invention:

1. In combination, a container of transparent material having liquid therein, an element 75 submerged in the liquid and having a downwardly facing concave side and means for delivering gas beneath the element, said element having two compartments and being rockably mounted, the arrangement being such that gas is first delivered into one compartment, to cause the element to swing and release a bubble, and when so swung to dispose the other compartment to receive gas.

2. In combination, a container having 85 liquid therein, a base plate within the container, an element submerged in the liquid and having a downwardly facing concave side, means for delivering gas beneath the element, said element arranged over said base plate 90 and having two compartments, and being rockably mounted, the arrangement being such that gas is first delivered into one compartment to cause the element to swing and release a bubble, and when so swung to dispose the other compartment to receive the gas.

3. In combination a container having liquid 95 therein, an element submerged in the liquid

and having a downwardly facing concave side and means for delivering gas beneath the element, said element comprising two compartments and being rockably mounted, the arrangement being such that gas is first delivered into one compartment to displace the liquid therein and cause the element to swing

and release a bubble, and when so swung to dispose the other compartment for receiving gas.

10

In witness whereof, I have hereunto set my hand this 27th day of December 1927.

HANS M. BOE.
